ACCOUNTING MACHINE

Merle E. Gould, Greenwich, Conn., assignor to
 Photoelectric Business Machines, Inc., New
 York, N. Y., a corporation of Delaware

Application March 12, 1940, Serial No. 323,499

3 Claims. (Cl. 235—133)

This invention relates to accounting machines and one of the important objects is to provide mechanisms whereby a rapid succession of value amounts may be added in the machine. The particular form of device for effecting entry of the successive value amounts into the machine is in the present case shown as a moving film carrying spots to represent different value amounts, and the light rays controlled by these spots operate through intermediate mechanisms to actuate the counters of the accumulative mechanism of the machine.

The present application constitutes a continuation in part of my co-pending application Serial No. 173,727, filed November 9, 1937.

In the present invention provision is made whereby the data accumulating mechanism is arranged for speedy operation, so that it is adapted for use in an accounting machine controlled by photographic film records on which data are represented by photographic spots, which spots designate the value of the recorded data by their positions on the film records. The spots are analyzed by light rays which activate photocells disposed in predetermined coded positions, corresponding to the positions of the coded designations on the records, to control the entry control means of the data accumulating mechanism. In the electrically controlled accounting machines, generally the practice is to operate the data accumulating mechanism in timed relationship with the movement of the records to effect differential displacements of the accumulating or adding elements. This principle of operation is not readily applicable to control remotely situated accumulating mechanisms. Therefore, further provision is made in the present invention whereby the operation of the accumulating mechanism is independent of the operating mechanism for feeding the records, consequently rendering it applicable for being controlled at remote locations by the record sensing means.

It is well recognized that photographic films of this sort customarily travel at high speed; therefore in any machine which involves the rapid entry of successive value amounts, the time factor of taking care of the carry-over operations from one adding wheel to the wheel of the next higher order, becomes important.

The tens carry operations in the usual accumulating mechanisms are effected directly after each item entry, so that considerable time is consumed, in addition to the normal entry time, to allow the carry operations, made necessary

5 by each item entry, to occur. This tens carrying time is reduced in the present invention by storing and counting the carry operations as they occur, but entering them into the proper denominational orders of the accumulating mechanism only after all items pertaining to a particular run, or operation of the machine, have been entered. The items can thus be entered as fast as the accumulating mechanism is capable of operating, no active machine time between successive item entries being necessary to allow for tens carry operations.

10 The arrangement of the accumulating mechanism for this delayed tens carry operation consists of an accumulator element for each denominational order, but with no mechanism for effecting tens carry operations directly from each element to the element of the next higher order. Each denominational order element has a carry-over storage system, each comprising a settable switching means, associated therewith, one of which receives a step of movement every time the associated accumulator element passes from "9" to "0." Each storing device, higher in a 15 series, receives a step of movement every time the next lower device in the series passes from "9" to "0." These series of storing devices, therefore, count and store any number of tens carry operations, separately, for each denominational order. At the end of the machine run, or when the desired number of items have been entered, the series of storing devices are read out and the stored carry units entered into the proper 20 accumulator elements.

25 30 35 Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is an enlarged view of a fragmentary section of the photographic control element.

Fig. 2 is a diagrammatic view of the film feeding and sensing means.

Fig. 3 is a perspective view showing in simplified form several orders of the data accumulating mechanism.

Fig. 4 is a circuit diagram showing the wiring connections of the machine.

Photographic control record

Referring now to Figs. 1 and 2, the control element of the machine is shown to comprise a continuous photographic film 15, provided with the usual feed apertures 16, and consisting of

individual areas or frames 17, which frames, when suitably recorded with data designations, form the individual control records.

In the use to which the invention has been applied, the film is opaque and is provided with data designations, such as transparent areas, or spots 18, which are suitably formed at predetermined index point positions on the individual frames. The differently disposed transparent areas, or spots represent the values of the data by their relative positions on the individual records. In practice, and according to the embodiment shown, the data designations are shown on the record in an index point relationship, corresponding to the arrangement of the index perforations on the perforated cards of the well known Hollerith accounting system; that is, the differential positions of the spots 18 delineate the particular values of the data represented thereby. The differential positions are represented by the dotted lines 19 in Fig. 1. The differently positioned spots are formed in adjacent columns on the records, which columnar positions are indicated by the dotted lines 20 in Fig. 1. In this figure it is noted, for example, that the designations, or spots 18 shown, represent the number "28."

Each individual record may be provided with spots in certain positions other than the data index point positions, just referred to, for purposes other than representing data. For example, a control designation is shown in Fig. 1 to be represented by the spot 21 which is provided in a position located below the zero index point position and between the described columnar positions. The purpose of this, and other, control designations which may appear on the records will be understood as the description progresses.

Record feeding means

In Fig. 2, suitable feeding means for the film 15, is shown diagrammatically, and represented generally by the reference character 22. The feeding means referred to comprises a conventional type of motion picture projection machine, and includes a source of light rays 23, a lens system 24, and a driving motor 25, connected to the projector drive shaft 26. The conventional projection machine is one in which the film is momentarily arrested opposite the lens system 24, while exposed, and in which the film is obscured by a shutter as the individual film frames are positioned successively to the lens system. Such projection machines are well known, and for this reason it is believed unnecessary to give further detailed description of this mechanism. For example, a suitable machine for use in conjunction with the present invention is the standard Bell & Howell film projection machine, the principles of operation of which are described in the U. S. Patent #1,075,407.

Record sensing means

Referring to Fig. 2, it is seen that in addition to the light source 23, and lens system 24, the record sensing means includes a plurality of light responsive, or photoelectric means, such as the bank of photocells 27. The individual photocells are arranged in a coded position corresponding to the coded arrangement of the spots 18 on the film records; that is, the photocells are arranged in separate columns, or orders, each column including as many photocells as there are index point positions in each column of the individual film record. In the present embodiment,

ten photocells are shown in each column to correspond to the ten index point positions for the data designations formed on the records, and are numbered accordingly, namely "9" to "0."

The banks of photocells are suitably disposed with respect to the lens system 24, of the projection machine, so that, as the film is being passed therethrough, at each exposure of a frame 10, 17, a pattern of light beams, corresponding to the coded spots formed thereon, will be projected upon the banks of photocells, whereby the photocells in certain coded positions will be activated by the beams, or rays, of light passing through the coded spots. It is understood that the light rays passing through the spots 18, formed in certain coded positions will activate those photocells disposed in the corresponding coded positions in the banks of photocells. For example, 15 the spots 18, on the frame 17, in Fig. 1, represent the number "28" and, upon exposure of said frame in the projector, the light rays passing therethrough are projected upon the banks of photocells to activate those photocells disposed in the corresponding coded positions, namely "28" which are indicated by the darkened areas.

The position, or station, at which the film frames are arrested momentarily (opposite the lens system 24), will be referred to as the sensing station, or position. The circuits energized by the activated photocells will be described presently.

For the sake of simplicity, only several columns of photocells are shown. However, it is understood that the number of columns of photocells provided should correspond to the number of columns of data designations provided on the film records. The photocells referred to, up to now, are those which are controlled by the data designations appearing on the individual records.

It is to be noted that additional photocells 28 and 29 are provided, for certain control purposes, which will be described later. It is only necessary to state, at this time, that the positions of the photocells 28 and 29, in the bank, correspond to the coded positions where a control designation may appear on the film records. For example, the photocell 28, is disposed in a coded position corresponding to the coded position where the control designation 21 may appear on the film records.

Data accumulating mechanism

Referring now to Fig. 3, several orders of a suitable data accumulating mechanism are shown, in simplified form, the operation of each order being the same, it will suffice to describe the elements, and operations thereof, relating to only one of these orders. The arrangement for effecting the displacement of the individual accumulator wheels 38 is conventional and based upon the disclosure made in the U. S. Patent #1,270,471 issued to Wahl, June 20, 1918. In the said patent, there is shown the well known mechanism whereby, when a selected key is manually depressed, a gear section (element 101 in Fig. 3 of the patent) is rotated, through a predetermined angle, to position a register wheel for indicating the digital value of the depressed key. Since this type of mechanism is old and well known, it is believed that the following brief description of the accumulating mechanism will suffice, for those skilled in the art, to understand the principles of operation employed in the present invention.

Each denominational order of the accumulating mechanism is provided with a common operating shaft 30, and a gear sector 31, which is secured to the said shaft. A plurality of arms 31a are fixed to and spaced on the shaft 30 in a spiral arrangement. A control solenoid 56 is associated with each arm 31a, having a related plunger 56a adapted to engage a corresponding arm. The plungers 56a, for each order, are the same in length, as shown in the figure, but, due to the spiral arrangement of the arms 31a, with respect to the plungers 56a, the different arms are rotated through different angles, upon selective energization of the related solenoids. The spirally arranged arms 31a are disposed in the paths of the strokes of the related plungers 56a, but are engaged at different times during the strokes of the said plungers, due to the said arrangement of the arms on shaft 30. The plungers 56a each have the same limited extent of movement and the differential actuation of the shaft 30 and sector 31 is determined by the extent of the lost motion before an operative plunger engages and actuates its arm 31a. For example, upon energization of the "1" solenoid, the shaft 30 will be rotated one unit; and upon energization of the "2" solenoid, the shaft 30 will be rotated two units, and so on.

It is evident that, upon successive energization of the said solenoids, the gear sector 31 is rotated through different angles, in accordance with the selective and successive energization of the control solenoids. Rotation of the gear sector causes the associated order wheel 35 to be displaced, or rotated, through corresponding angles, for instance, upon energization of the "1" solenoid, the shaft 30 and sector 31 are rotated to advance the wheel 35 one unit or step, thus effecting the entry of "1"; and upon energization of the "2" solenoid, the said shaft and sector are rotated to advance the wheel two units or steps, thus effecting the entry of "2," etc.

The arrangement for effecting advancement of the wheel 35, which is rotatably mounted on shaft 33, comprises a ratchet wheel 36, secured to shaft 33, and a cooperating pawl 34, which pawl is pivotally mounted on a mutilated gear 37. The said gear 37 is pinned to the wheel 35, so that, upon rotation of shaft 33, by means of the gearing 32, and sector 31, the ratchet wheel 36 is rotated to drive the gear 37 and wheel 35, through the said cooperating pawl. In this manner, entry of the items or data can be made in each denominational order of the accumulating mechanism. Upon each item entry operation, the selected control solenoid is deenergized, permitting the sector 31, shaft 30, and arms 31a to be restored to the normal position, shown in Fig. 3, by the conventional means, shown in the aforementioned patent. This conventional means is shown herein in Fig. 3 as the spring attached to the sector 31.

It was mentioned that transferring of the tens carry, from the related order to the next higher order, is not effected at the time item entries are made, but instead are stored and counted in suitable storing devices, associated with each order. Referring again to the units order, shown in Fig. 3, several storing devices of a series are shown, and indicated generally by the reference characters 43 and 44 (also see Fig. 4). Each device comprises an arcuate bank of stationary contacts 46, which are engaged successively by the rotatable conducting arm 47. The said conducting arms of the devices 43 and 44 are secured to shafts 48 and 49, respectively.

Gears 39 and 40 are also secured to shaft 48, the former being rotated a partial revolution by the tooth 38 of gear 37 whenever the wheel 35 passes from "9" to "0." The ratio of gears 37 and 39, being such that each partial revolution of gear 39 comprises one-tenth of a revolution and is sufficient to rotate the shaft 48 and advance the conducting arm 47 to engage the next adjacent contact 46 of the arcuate bank. Upon the completion of each half of a full revolution of gear 39, the gear 40 is arranged so that one of the teeth 41 engage the gear 42, secured to shaft 49, to effect rotation of the gear 42 one-tenth of a revolution, or one step. Gear 42, being secured to shaft 49, thereby causes the conducting arm 47 of storing device 44 to be advanced, to engage the next adjacent contact 46 of its arcuate bank. It is noted that each contact of each device represents a digital value, which is indicated accordingly in Fig. 4. It will be noted that each one-half revolution of gear 39 and related conducting arm 47 is representative of ten stored carries and that during each one-half revolution, the conducting arm 47 sweeps across each of the contacts 46. It should now be understood that each time successive item entries are made, for example, in the units order, to cause the associated accumulator wheel 35 to pass from "9" to "0," indicating that a tens carry operation should be made, from the units order to the tens order, an entry of one is made into the carry storing device 43; and that for each tenth carry entry in the lower order storing device 43, an entry of one is made into the next higher order storing device 44, and so on. In this manner the tens carries are entered and stored in each of the storing devices described. In order to simplify the description, only two storing devices 43 and 44 are shown associated with the units order, and one storing device 45 is shown associated with the tens order of the accumulating mechanism, said device 45 being identical in structure and operation to the devices 43 and 44, just described.

Operation of the machine

Referring now to Fig. 4, the operation of the machine will be described. It is to be understood from the description thus far that the term "data accumulating mechanism or means" refers to a plurality of the denominational orders, each order comprising the elements just described, and the one or more carry storing and counting devices, and associated control means, associated with each of the said orders.

In the machine, illustrated in the figures, two orders of photocells, and three orders of the accumulating mechanism are shown, and to simplify illustration of the invention, the machine is described as having a restricted data accumulating capacity, but it will be evident that the capacity of the machine may be enlarged to any desired capacity by employing additional orders of photocells and corresponding additional orders in the accumulator, just described, and connected in the machine similarly as the units shown in the present circuit diagram for the machine.

Now, let it be assumed that the projection machine is set into operation to feed continuously the photographic film, but as mentioned before, presenting the film frames intermittently to the sensing position, where the coded designations, appearing on the individual records or frames, permit the rays of light to pass there-

through, momentarily, to activate only the photocells which are disposed in the coded positions corresponding to the coded positions of the data designations. It is assumed that the speed of operation of the projection machine is adjusted so that the individual film frames are presented to the sensing station at a rate at which the data accumulating mechanism is capable of manifesting the sensed data. It is assumed, further, that the individual frame, or record, presented momentarily to the sensing station bears data designations, or spots, representing the number "28," thus causing the "2" cell of the tens order and the "8" cell of the units order to be activated.

Due to the activation of the said cells, current is permitted to flow in the following circuits: grounded battery 50, normally closed switch 51, conductor 52, the "8" photocell of the units order, conductor 53, the "8" solenoid 56 of the units order, conductor 57, switch 58 to ground 59, energizing said solenoid; the other circuit can be traced from grounded battery 50, to the switch 51, conductor 52, the "2" cell of the tens order, conductor 54, normally closed contacts 55, the "2" solenoid 56, conductor 57, switch 58 to ground 59, energizing the said solenoid. Energization of the said solenoids causes entries of "8" items to be made in the accumulator wheel 35 of the units order, and "2" items in the wheel 35 of the tens order, in the manner as described hereinabove. It is seen, therefore, that during the record sensing operations, the said photocells of each order are activated selectively, in accordance with the data designations on the records to control, selectively, the energization of the related control solenoids of the corresponding order, thereby causing the sensed data to be entered into the accumulating mechanism accordingly.

In order to simplify the showing of the circuit connections in the wiring diagram in Fig. 4, the conventional amplifiers have not been shown connected in the individual photocell circuits. Since the conventional photocell controlled amplifiers are so well known, at this date, it is deemed sufficient to mention that the conventional type of amplifier can be used in each photocell circuit for amplifying the current flow directed to the related solenoids 56. In view of this disclosure, additional showing in the drawings is not deemed necessary, for those skilled in the art, to understand the principles of operation of the present invention.

Now, in order to describe briefly the method of reading out the stored carries, assume that, at the end of a machine run, 166 items are entered in the units order of the main accumulator, and 12 items in the tens order. The true total of these items is 286; however, at the end of the said machine run, before reading out the stored carries, the wheel 35 of the units order is standing at "6," the wheel 35 of the tens order at "2," and the wheel 35 of the hundreds order at "0," so that the main accumulator shows the uncomplicated total, 026. The conducting arms 47 of the carry-over storing devices 43 and 44 of the units order are engaging the "6" and "1" contacts of the respective arcuate bank of contacts 46, and the conducting arm 47 of the device 45 of the tens order is engaging the "1" contact of the related contacts 46.

During the read out operations to be described, the normally closed contacts 51 and switch 58 are opened. The first step, in reading out the stored carries, comprises manually positioning

the conducting arm 60, of the sequence switch 61, to engage the contact 62, thus establishing a circuit from grounded battery 50 to conductor 64, conducting arm 60, contact 62, conductors 65 and 66 to the grounded coil of relay 67, energizing said relay. Upon energization of relay 67, the associated contacts 68 are opened, and contacts 68, 69, and 70 are closed. Since the contacts 69, which are now closed, are connected to the common conductor 65, the circuit from grounded battery 50, just traced, is continued to include contacts 69, conducting arm 47 of device 43, the "6" contact of the associated bank 46, conductor 71, the "6" solenoid 56 of the tens orders, conductors 57 and 72, contacts 68 to ground, energizing said solenoid, and effecting the entry of "6" in the wheel 35 of the tens order, thus causing the said wheel to stand at "8." Also, since contacts 70 (now closed) are connected to the common conductor 65, the circuit from grounded battery 50, just referred to, is extended to include the said contacts 70, conducting arm 47 of the device 44, contact "1" of the associated bank of contacts 46, conductors 73 and 74, the "1" solenoid 56 of the hundreds group, conductors 57 and 72, contacts 68 to ground, energizing said solenoid, and effecting the entry of "1" in the wheel 35 of the hundreds order, thus causing the said wheel to stand at "1."

It is obvious that the reading out of these amounts 6 and 1 out of the tens order and the hundreds respectively of the main accumulator, takes place simultaneously for the two orders, that is, the tens and the hundreds.

Whenever this reading out from the units storage, for example, into the tens order (of the main accumulator) should move this tens wheel from 9 through 0, then a carry-over would be due to go into the hundreds wheel of the main accumulator; but there being no direct carry-over between these two wheels, this carry-over is merely stored-up in the storage system for the tens order wheel so that there would be no confusion or loss of this carry-over in case the hundreds wheel was at that time moving under the carry-over from the unit storage system.

The next step in the present reading out operation comprises positioning the conducting arm 60 to engage the contact 63, thus connecting the grounded battery 50, by means of conductor 64, conducting arm 60, and contact 63 to the common conductor 75. The grounded coil of relay 76 is connected directly to the said common conductor 75, thereby causing the relay to be energized, to close the associated contacts 77. The said conductor 75 is also connected to the conducting arm 47 of the storing device 45 by conductor 78, thereby permitting current from the grounded battery 50 to flow in the following circuit, comprising the "1" contact of the bank of contacts 46 of the tens order, which is engaged by the related conducting arm 47, conductor 74, the "1" solenoid 56 of the hundreds order, conductor 57 and contact 77 to ground, energizing said solenoid and effecting the entry of "1" in the wheel 35 of the hundreds order, thus causing the said wheel to stand at "2."

It is seen now, upon completion of the tens carry read out operation, that the said accumulator wheels 35 are standing at "2," "8," and "6," to represent the true total of the items, or data sensed on the individual records. Upon restoration of the conducting arm 60 to the normal position shown in Fig. 4, closure of switches 51 and 58, resetting of the conducting arms 47 of

the devices 43, 44, and 45 to zero, and resetting the accumulator wheels 45 to zero (which operations are assumed to be manually operated for the present description), the machine is conditioned for sensing other groups of records, and controlling the accumulating mechanism accordingly to effect entries of the data therein, exactly as described hereinabove.

It was mentioned before that provision is made for selecting predetermined accumulating mechanisms, from a plurality, upon sensing certain control designations, recorded on the records, and then effecting entry of the related data on the records into the selected mechanism or mechanisms. A suitable arrangement for effecting this type of operation will now be described.

Referring now to Fig. 4, a second accumulating mechanism is shown diagrammatically and designated ACC #2, which is similar to the accumulating mechanism described hereinabove and designated ACC #1 in Fig. 4. The same reference characters, provided with the suffix *a*, are employed for designating the elements of the mechanism ACC #2, similar to the elements of the mechanism ACC #1.

For the present description, assume that the individual records are provided with a control designation 21, in addition to the data designations 18 (see Fig. 1). It was pointed out that the said control designations control the activation of photocell 28. Assume also that switch 58 is opened during the operations to be described.

Upon sensing the said designations disposed on the individual records, it is to be noted that the activation of the photocells 27, upon sensing the data designations, is not effective at this time to effect energization of the related solenoids 56, due to the fact that the common conductor 57 is not connected to ground. However, a ground connection to the said common conductor is made upon energization of relay 80, the energization of which is under control of photocell 28. Upon activation of the said photocell 28, the following circuit is established: from grounded battery 50 to switch 51, conductor 52, photocell 28, relay 80, conductor 84, normally closed contacts 81 to ground 83, energizing said relay. The contacts 81 and 82 of relay 80 are of the "make before break" type. Therefore, it is seen that ground 83 is connected to contacts 82 before contacts 81 are opened. Upon closure of contacts 82, and connection of ground 83 to conductor 57, it is evident that the solenoids 56 of the various orders of ACC #1 can now be energized in accordance with the activated cells 21. A circuit for one order can be traced as follows: grounded battery 50, switch 51, conductor 52, photocell 27 of the units order, for example, related solenoid 56, conductor 57, contacts 82 to ground 83, energizing the said solenoid. The adjustment of contacts 81 and 82 is such that contacts 81 are not opened until the selected solenoid 56 is sufficiently energized to render the associated plunger effective to position the related shaft 30.

Now assume that the records which are sensed are provided with control designations disposed so that the photocell 29 is activated whenever the individual records are presented to the sensing station. Relay 80a is then energized, each time the said control designation is sensed, by the circuit from grounded battery 50, switch 51, photocell 29, relay 80a, contacts 81a to ground 83a. Upon closure of contacts 82a, the said ground 83a is connected to conductor 57a thus permitting the selected solenoids 56a of the vari-

ous orders of ACC #2 to be energized in accordance with the sensed data.

In the event the sensed records are provided with a plurality of said control designations to activate photocells 28 and 29, simultaneously, both relays 80 and 80a are energized to connect the grounds 83 and 83a, respectively, to the corresponding conductors 57 and 57a, thus controlling both ACC #1 and ACC #2 in accordance with the sensed data.

10 The carry storing devices 43a, 44a, and 45a of ACC #2 are read out exactly as the devices 43, 44, and 45 of ACC #1, so that further description of the carry read out operations is not deemed necessary.

15 In summarizing the construction and operation of the carry-over storage arrangement above referred to, it will be seen that the main accumulator with its plurality of denominational-order wheels, does not have the usual carry-over mechanisms between the successive wheels,

20 so that at the end of a continuous run of entries of amounts, the main accumulator shows a reading which is lacking the entry of the successive carry-overs. These carry-overs are stored up in a series of carry-over systems, there being one complete or multi-wheel storage device for each one of the denominational-order wheels of the main accumulator. That is, since these carry-over devices do not receive the same rapid and differential actuations as is the case with the main accumulator, each of said devices comprises a plurality of denominational-order wheels wherein supplementary carry-over devices are provided from the lower order units to the next higher order wheels, there being ample time to effect these carry-overs.

25 30 35 By these mechanisms a rapid and continuous run of entries of value amounts may be made upon the main accumulator and any number of successive carry-overs can thus be stored up, numbering if necessary into the hundreds or thousands, etc., without limitation, such number being limited only by the capacity of these storage wheels which register the numbers added thereon as in any ordinary counter.

40 45 Then at the end of the continuous run of amount entries, the read-out mechanisms are operated to bring the main accumulator reading to its correct final reading. These read-out mechanisms are operated in sequence, first the storage device for the unit wheel of the main counter, then the carry-over storage device for the hundreds wheel of the main counter, and so on to complete in sequence the reading out for all of the storage devices.

50 55 60 65 70 If in this process, as above explained, one of the wheels of the main counter passes through its position from 9 to 0, its corresponding carry-over system is actuated to add 1 thereon, but this carry-over is not lost, because it is then properly entered when the next succeeding storage device is read out. In this way, by the sequential operation referred to, all of the storage carry-over devices are read out one after the other, whereby the main accumulator is brought to a correct final reading of the total of the continuous run of amount entries.

75 While there has been shown and described and pointed out the fundamental novel features of the invention as applied to a single modification it will be understood that various omissions and substitutions and changes in the form and details of the device illustrated and in its operation may be made by those skilled in the art

without departing from the spirit of the invention. It is the intention, therefore, to be limited only as indicated by the scope of the following claims.

What is claimed is:

1. In an accounting machine, in combination, an accumulator comprising a plurality of main denominational-order wheels; actuators for effecting differential value movements of said accumulator wheels; denominational setting elements for controlling the said actuators; carry-over storage devices for each of said main denominational-order wheels, each of said devices comprising a plurality of settable denominational-order storage units and having supplementary carry-over devices between lower order storage units and next higher order units, whereby to store up any number of carry-overs from any accumulator wheel during a continuous run of entries of amounts in the main accumulator; means on each main denominational-order wheel for causing a unit advance of the related carry-over storage device when said wheel passes from 9 to 0; and read-out mechanism for transferring in sequence, first from all of the units of the storage device for the lowest order to the wheels of higher order in the main accumulator, then from all of the units of the storage device for the next order to the wheels of higher denominational order in the main accumulator whereby to bring the main accumulator to a correct final reading of the total of the said continuous run of amount entries.

2. In an accounting machine, in combination, an accumulator comprising a plurality of main denominational-order elements; means for effecting entries in said accumulator; carry-over storage devices for each of said main denominational-order elements, each of said devices comprising a plurality of settable denominational-order storage units and having supplementary carry-over devices between lower order storage units and next higher order storage units, whereby to store up any number of carry-overs from any accumulator wheel during a continuous run of entries in the main accumulator; means on each main denominational-order element for causing a unit advance of the related carry-over storage device when said element passes from 9 to 0; and read-out mechanism for transferring in sequence, first from all of the units of the storage device for the lowest order to the elements of higher order in the main accumulator, then from all of the units of the storage device for the next order to the elements of higher denominational order in the main accumulator whereby to bring the main accumulator to a correct final reading of the total of the said continuous run of entries.

3. In an accounting machine, the combination set forth in claim 1, wherein the read-out mechanisms comprise a plurality of electromagnetic devices with circuits connected therewith for differentially actuating the corresponding next higher order wheels of the main accumulator.
